UNITED STATES PATENT OFFICE.

HARVEY B. REPETTO, OF WHEELING, WEST VIRGINIA, ASSIGNOR TO WHITAKER-LESSNER COMPANY, OF WHEELING, WEST VIRGINIA, A CORPORATION OF WEST VIRGINIA.

OIL STOVE.

1,402,315.

Specification of Letters Patent. Patented Jan. 3, 1922.

Application filed January 10, 1921. Serial No. 436,153.

To all whom it may concern:

Be it known that I, HARVEY B. REPETTO, a citizen of the United States of America, and resident of Wheeling, county of Ohio, 5 and State of West Virginia, have invented certain new and useful Improvements in Oil Stoves, of which the following is a specification.

This invention relates broadly to oil stoves, 10 and more particularly to oil heating stoves of that type in which a plurality of lamp burners are carried by an oil container.

The primary object of the invention is to provide an oil heating stove of lamp type 15 having means whereby the wick-carrying lamp burners are shielded from drafts of air which would tend to disturb the regularity of the flames of said burners, or produce objectionable flickering, and also whereby said 20 burners, are concealed from view for improving the appearance of the stove.

A further object is to provide a burner shield which may be conveniently moved or swung to an out-of-the-way position to permit 25 of ready access to the burners.

With these and other objects in view, the invention resides in the features of construction and arrangement which will hereinafter be fully described, reference being had to the 30 accompanying drawings, in which—

Figure 1 is a perspective view of an oil heater equipped with the invention, and—

Figure 2 is a partial vertical section of the same showing the oil container partially 35 withdrawn from the stove casing.

Referring to said drawings, 1 indicates a stove casing of a more or less common open-front type having an oil container or tank 2 of drawer-like form adapted for sliding 40 movement into and out of its operative position within the casing. Said container carries a plurality of alined lamp-burners 3 which support thereon in the manner common to such burners glass lamp chimneys 4.

45 Carried by the container 2 in front of the burners 3 and suitably attached to said container, as by means of hinges 5, is the lower edge portion of a shield 6 which serves to protect or shield the burners from drafts of 50 air that would otherwise have direct access to said burners and interfere with normal burning—that is, produce irregular or fitful burning. Said shield, which is preferably formed of sheet metal, is approximately of

arcuate form in cross section, extending upwardly and inwardly from its point of attachment to the container and having its free edge closely approaching the chimneys 4 above, or in overhanging relation to, the tops of the burners. The said free edge of 60 the shield is preferably of serrated form, providing alternate tongues 6^a and recesses 6^b, the former projecting inward between adjacent chimneys, and the latter having a contour substantially corresponding to that of 65 the embraced portions of the chimneys.

When access to the burners 3 or to the filler opening 7 is desired, the shield is swung outward on its hinges or other similar pivotal mounting. In operative position the shield 70 not only guards the burners against drafts, but also serves to conceal the burners from view so that an improved appearance is presented by the stove.

What is claimed is—

1. In an oil stove, the combination with 75 an oil container having mounted thereon a plurality of lamp burners adapted for carrying lamp chimneys, of a member mounted on said container in front of said burners 80 and normally extending upward and inward into shielding relation to said burners.

2. In an oil stove, the combination with an oil container having mounted thereon a plurality of lamp burners adapted for carrying 85 lamp chimneys, of a member pivotally mounted in front of said burners and normally extending upward and inward into shielding relation to said burners, said member being adapted for movement to a retracted position to permit access to said 90 burners.

3. In an oil stove, the combination with an oil container having mounted thereon a plurality of lamp burners adapted for carrying 95 lamp chimneys, of a member mounted on said container in front of said burners and normally extending into partially overlying shielding relation to said burners, said member being pivotally attached to said container and adapted for swinging outward to inoperative position to permit access to 100 said burners.

4. In an oil stove, the combination with an oil container having mounted thereon a 105 plurality of lamp burners adapted for carrying lamp chimneys, of a metal shield carried by said container in front of said burn-

- cluding a lateral chamber and an upper flared portion providing a valve seat, a partitioning member including a tongue adapted to be positioned within the lateral chamber, 5 a vent pipe in communication with the lateral chamber, means carried by the vent pipe and contacting with the tongue for securing the partitioning member within the lateral chamber, means forming a part of 10 the partitioning member for directing a quantity of the water passing through the valve to the lateral chamber, and a valve for controlling the passage of water through the body portion.
- 15 3. In a valve construction, a body portion having a valve seat and a lateral chamber, a vent pipe in communication with the lateral chamber, a partitioning member within the lateral chamber, a pin carried by the 20 vent pipe and adapted to contact with the partitioning member for securing the same against movement, said partitioning mem-
- ber adapted to direct a quantity of fluid into the vent pipe, and a valve for controlling the passage of fluid through the body portion. 25
4. In a valve construction, a body portion having a valve seat and a lateral chamber, a vent pipe, a partitioning member positioned within the lateral chamber and having an enlarged portion extending into the body portion for directing a quantity of fluid into the lateral compartment, means carried by the vent pipe for securing the partitioning member against movement, and a 30 valve for controlling the passage of fluid therethrough. 35

In testimony that I claim the foregoing as my own, I have hereto affixed my signature in the presence of two witnesses.

ALFRED E. POWELL.
